W. C. POWELL.

UNION GARMENT.

APPLICATION FILED MAR. 30, 1914.

1,112,720.

Patented Oct. 6, 1914.

UNITED STATES PATENT OFFICE.

WILLIAM C. POWELL, OF ST. JOSEPH, MISSOURI.

UNION GARMENT.

1,112,720.

Specification of Letters Patent.

Patented Oct. 6, 1914.

Application filed March 30, 1914. Serial No. 828,270.

To all whom it may concern:

Be it known that I, WILLIAM C. POWELL, residing at St. Joseph, in the county of Buchanan and State of Missouri, have invented 5 certain new and useful Improvements in Union Garments, of which the following is a specification.

My invention has for its object to provide an improved union garment which may 10 be made up as over-all, night suit, work clothes or other similar garment, the invention being, however, especially useful when applied to over-all for firemen, automobile users and others requiring a dust 15 proof garment so constructed as to permit great freedom of motion of the body, and one which can be easily put on and taken off and held on the person without the employment of suspenders or the like.

20 In its general nature, the invention resides in providing a garment in which the trousers and body sections are united into one structure along the front half of the waist line (or if desired, the entire front 25 of the garment may be made in two pieces, a right and a left), the front of the garment opening up from the crotch to the neck and provided with buttons and button holes to close the opening, the rear or seat portion 30 of the trousers section being unconnected with the back of the jacket or body section from hip to hip, the trousers section being opened down the side from the waist line to a point about in alinement with the 35 crotch, the back of the jacket having a skirt so designed as to be tucked in beneath the seat of the trousers section and lie flat against the body or it may be left out and when left out the skirt is of a length sufficient 40 to cover the opening in the hip pockets when such are employed, means being also provided for securing the trousers section snugly against the body of the user, the side openings of the trousers section and 45 the front opening of the garment being provided with flaps, buttons and button holes to enable the same to be closed.

In its more subordinate nature, the invention also includes those novel details of 50 construction, combination and arrangement of parts, all of which will be first fully described, then be specifically pointed out in the appended claims, and illustrated in the accompanying drawings, in which—

55 Figure 1 is a perspective view illustrating my invention in use in one of its forms

as an over-all. Fig. 2 is a side elevation of a portion of the same, showing the skirt tucked in. Fig. 3 is a view similar to Fig. 2, showing the seat portion let down. Fig. 4 is a view similar to Fig. 2, showing the skirt on the outside. Fig. 5 is an enlarged detail view showing the manner of buttoning the side openings of the trousers section, the upper button being buttoned onto the 60 inner flap of the pocket and invisible, while the lower button buttons through the trousers section below the pocket mouth and is visible. Figs. 6 and 7 are detail views of slight modifications. Fig. 8 is a perspective 65 view showing how the invention may be made up as a night garment or the like. Fig. 9 is a view similar to Fig. 3 of the garment shown in Fig. 8. Fig. 10 is a rear elevation of a portion of the invention showing 70 a modification in the waist line securing means. Fig. 11 is a detail perspective view showing another modification. Fig. 12 is a detail view showing another way of securing the garment around the waist. Fig. 75 13 is a detail perspective view showing a further modification in the waist line securing means. Fig. 14 is a rear elevation showing a slight further modification in the belt holding loop.

80 In the drawings, in which like letters and numerals of reference indicate like parts in all of the figures, 1 is the trousers section of the garment which is usually made in four pieces, the front of the trousers section being 85 permanently secured to the front of the body section, by suitable stitching, as at 20, or made integral therewith, as shown in Figs. 7 and 9. The front of the body section consists of two half parts 13—14 (see 90 Fig. 1), corresponding to the two half parts of the front of the trousers section, and the trousers section and body section are opened up, the front, as at 12, from the crotch to the neck opening, and provided with suitable 95 buttons and button holes to close the opening in the usual manner. The back trousers sections 2 are sewn at 3 to the front sections from the bottom of the leg upwardly to a place 4 about in alinement with the 100 crotch, and from that point 4 to the point 5 at the waist line, the front and back parts of the trousers section are left unsewn but are secured by buttons and button holes 7, 8 and button 10. The button 10 is arranged 105 in close proximity to the waist line, and the button 7, about half way between the but-

ton 10, and the point 4, and just below the bottom of the mouth of the side pocket of the garment, to leave an opening 6 between the button 7 and the point 4, and the opening between the mouth 9 of the pocket 11 and the flap of the seat portion of the trousers section through which the band of the user may be inserted to get at the pockets of the under garments. The jacket or body portion of the garment is composed of two front portions 13-14, shaped to fit, and the back 16, which may also be made in two parts sewn together, however, to form an integral structure, the back 16 being sewn 15 along the sides 15 to the front sections 13-14, from the top down to the point 5 at the waist line, the back 16 being continued below the waist line to form a skirt 24 which forms one of the essentials of my present 20 invention, the skirt 24 being of a length sufficient to project over the mouths of the hip pockets 23, when such are used, and the skirt 24 is left to lap on the outside, or the skirt may be tucked in, as shown in Fig. 2, 25 to lie smoothly against the seat portion of the garment and against the wearer.

In order to hold the trousers section of the garment in place and relieve any supporting weight from the shoulders, a belt 30 22, or its equivalent, is provided, the trousers section of the garment having suitable loops or belt guides 21, through which the belt is adapted to pass. The sleeves 25 are made either with button cuffs, as shown in 35 Fig. 1 or in any other desired way.

I have indicated several modifications of the means by which the trousers section of the garment may be supported, and by reference to Fig. 6, one of those modifications 40 will be apparent. In the construction shown in Fig. 6, the belt 22^a is in the nature of a half belt and extends around the front half of the garment only, it being secured to the buttons 27, while a band 22^a is secured in 45 the waist line of the back or seat portion of the trousers section.*

In the modification shown in Fig. 7, the half belt 21^a is secured to the front of the trousers section and is buckled in back. 50 In the modifications shown in Fig. 10, the desired holding is acquired by means of short buckle and strap members 32, arranged at intervals around the waist line, preferably entirely in the back of the garment. 55

In the form shown in Fig. 11, the belt is in the nature of an elastic band that may be tied or otherwise secured in the front, while in the modification shown in Fig. 12, the seat curing member 28, that passes through the loops 21^a, is in the nature of a tape. 60

In the modification shown in Fig. 13, the belt member sections 29^a are integrally formed with the seat portion of the trousers section either as an integral part or

sewn permanently thereto in order to form an integral structure.

In the modification shown in Fig. 14, the belt holding loops 21^a are formed with the back of the trousers section, and bent over 70 and secured by suitable buttons or fasteners 21^a.

The essential characteristics of my invention, I desire it understood, is the making of the garment with the front opening from 75 the crotch to the neck, and the seat portion of the trousers section opening at the sides so as to be let down, the back of the coat section being provided with a skirt capable of being either tucked in or left out over the 80 back in such a manner as to cover the hip pocket openings or to give a coat or a blouse effect, as desired, the garment being supported at the waist by a belt or other equivalent similar arrangement, such as disclosed 85 in the drawing whereby the weight of the trousers part of the garment may be carried at the waist and not at the shoulders so as to enable the wearer to have free movements of the body without straining the garment 90 or interfering with the users actions.

Fig. 14 shows the collar 17 which is another important feature of the complete suit, since it may be buttoned tighter about the neck by reason of the button arrangement 95 shown, or it may be turned entirely up to give complete protection from dust or the elements.

Figs. 1 and 2 show a convenient pocket arrangement 18 and 19. 100

I am aware that heretofore a Patent No. 605,236 has been issued to one C. G. Smith, June 7, 1898, which, at first glance, might appear, to one not skilled in the art, as similar to my construction, and I do not 105 desire to be understood as claiming a garment such as is shown and described in the Smith patent. My garment differs from the Smith garment in many essential characteristics which will be clearly apparent to those 110 skilled in the art and which need not, I believe, be here fully set out.

From the foregoing taken in connection with the accompanying drawings, it is thought the complete construction, design, 115 arrangement and advantages of my invention will be clear to those skilled in the art.

What I claim is:—

1. A union garment comprising a jacket or body section and a trousers section, the 120 front of said sections being permanently secured together at the waist line from hip to hip and having a buttoned opening extending from the crotch to the neck, the seat of the trousers section being separated from the front at the sides from the waist line down to a place in approximate alinement with the crotch, side flaps and button connections between the front and the seat of 125 the trousers section, means carried by the 130

trousers section for drawing the waist line of the garment close to the body of the wearer to support the weight of the trousers section, the back of said body section having 5 a flat skirt adapted to extend over the upper portion of the seat of the trousers section to cover the upper edge of the same and project downwardly over the seat or be tucked in and lie smooth against the seat of 10 the wearer and expose the upper edge of the trousers section as may be desired.

2. A union garment comprising a body section and a trousers section shaped to the wearer, the front of the body section and the 15 front of the trousers section being formed as a pair of continuous half members vertically separated from the crotch to the neck and provided with buttons and button holes to secure the same, the rear of the trousers 20 section being formed separately and secured together from the crotch height down the legs to the bottom, the seat portion of said trousers section being separated along the side from the crotch height up to the waist 25 line and provided with a flap and button connection with the front, thereby forming a seat portion capable of being let down, the back of the body section having a flat skirt extending from hip to hip and adapted to be 30 projected out over the seat portion or tucked in smoothly to lie over the seat of the wearer and expose the upper edge of the seat portion of the garment, as desired, and a belt strap carried by the trousers section to hold 35 the same to the body of the wearer, hip pockets on said seat portion, the openings of said pockets being adapted to be covered by said skirt when the same is worn outside.

3. A union garment comprising a body 40 section and a trousers section shaped to the wearer, the front of the body section and the front of the trousers section being formed as a pair of continuous half members vertically separated from the crotch to the neck and 45 provided with buttons and button holes to secure the same, the rear of the trousers section being formed separately and secured together from the crotch height down the legs to the bottom, the seat portion of said 50 trousers section being separated along the side from the crotch height up the waist line and provided with a flap and button connection with the front thereby forming a seat portion capable of being let down, the back 55 of the body section having a skirt extending from hip to hip and adapted to be projected out over the seat portion or tucked in smoothly, as desired, hip pockets on said seat portion, the openings of said pockets 60 being adapted to be covered by said skirt when the same is worn outside, and side pockets carried by the front of said trousers section the opening of said side pockets be-

ing concealed and of less length than the length of said side openings, the flap and 65 button connection between the seat portion and the front of said trousers including visible buttons beneath the opening of the side pockets and invisible buttons in the mouth of the side pockets close to the waist 70 line.

4. A union garment comprising a front consisting of two vertical half members permanently connected at the waist line and having a button and button hole connection 75 in the front from the crotch to the neck, a back formed of two principal sections one a body section and the other a trousers section, said sections being permanently secured to the front along the sides from the waist 80 line up and from the crotch height down whereby to leave the seat portion of the trousers section unattached from the front at the sides from the crotch height to the waist line, the trousers section and the body 85 section being unattached from hip to hip and the body section having a projecting skirt adapted to be projected over the seat section to cover the upper edge of the same and project downwardly over the seat of 90 the garment to give a coat effect or tucked in to expose said upper edge of the seat section of the garment as desired, a button and button hole connection for securing the side 95 openings between the seat portion and the front of the trousers section, and a waist encircling means carried by the trousers section for securing the garment around the waist to support the weight of the trousers section.

5. A union garment comprising a jacket or body portion and a trousers section, the front of said sections being permanently secured together at the waist line from side to side and having a buttoned opening extending from the crotch to the neck, the sides of the trousers section being separated at the front from the waist line down to a place in approximate alinement with the crotch, button and button-hole connections 105 between the seat portion of the trousers section and the front of the trousers section, the seat portion of the trousers section from side to side being separate from the back of the jacket section, the back of the jacket 110 section including a flat skirt portion adapted to extend over the upper portion of the seat of the trousers section to give a coat effect, or be tucked in and lie smooth against the seat of the wearer and expose the upper edge 115 of the trousers section to give a blouse effect as may be desired.
